UNITED STATES PATENT OFFICE.

EDWIN G. MUMMERY, OF DETROIT, MICHIGAN.

VAPOR-BURNER.

1,273,173.

Specification of Letters Patent. Patented July 23, 1918.

Application filed February 16, 1918. Serial No. 217,645.

To all whom it may concern:

Be it known that I, EDWIN G. MUMMERY, a citizen of the United States of America, residing at Detroit, in the county of Wayne 5 and State of Michigan, have invented certain new and useful Improvements in Vapor-Burners, of which the following is a specification, reference being had therein to the accompanying drawings.

- 10 The invention relates to vapor burners designed for use in the combustion of hydro-carbon liquid fuels and more particularly designed for use with the less volatile fuels, such as kerosene. The invention has particular reference, first, to the means employed for controlling the distribution of the vapor around the burner tube; second, to the construction of the lighter; and third, to various novel features of constructions as 20 hereinafter set forth.

In the drawings:

Figure 1 is a perspective view of the burner showing the inner casing and lighter removed;

- 25 Fig. 2 is a vertical central section through the burner with the parts in operative position.

My improved burner is of that type in which the liquid fuel is introduced into a base ring which is in communication with an upwardly-extending annular burner tube having foraminous walls. When the burner is in operation the heat which is conducted to the base ring is sufficient to vaporize the 30 fuel which, passing upward between the foraminous walls, will be commingled with air so as to burn at the top with a blue flame. It is necessary, however, to provide means for first lighting the burner, and where relatively non-volatile fuels, such as kerosene, are used lighting is difficult. I have overcome this difficulty by connecting to one of the foraminous walls, and preferably the inner 35 one, an annular lighter member having a wick or other absorbent material which will be saturated with the liquid fuel. Provision is also made for lifting this wall to clear the other wall so that the wick may be easily lighted. In detail, A is the base ring, 40 preferably formed of pressed sheet-metal and having its inner side B extended upward, with perforations C in this extension. This perforated extension forms a portion of the inner wall of the burner tube, the 45 complementary portion of which is formed by an attachable foraminous tube D nor-

mally resting upon the wall B. E is the outer wall of the burner tube which is also foraminous. The base ring A is of greater width than the burner tube and its outer 50 wall F is of greater diameter than the foraminous tube E. G is a cap for closing the space between the walls F and E and for supporting the latter out of contact with the liquid in the ring A. As shown this cap G 55 is formed with the downwardly-extending outer flange H which closely fits outside of the wall F, and the cap is also provided with a downwardly-extending inward flange J terminating in an inwardly-extending ledge 70 J upon which the tube E rests. Thus the ring F, together with the cap G will form a vapor channel surrounding the base of the burner tube and forming a free passage for distributing the vapor therearound so as 75 to produce a uniform quantity of vapor in all portions of the tube.

As has been stated, the inner wall D of the tube rests upon the upward extension C of the base ring A. K is a lighter member 80 in the form of a ring, which holds a wick L, preferably of a non-combustible type, such as asbestos. The ring is provided with a plurality of upwardly-extending arms M having at their upper ends inwardly-extending hooks N adapted to engage perforations in the wall D. This will form a detachable connection between the burner and the wall D, such that by lifting the wall D the burner will also be lifted. At the upper end of the 85 wall D is a lifting handle O, preferably formed of wire and having its ends extended at P to form a centering guide for the wall D in relation to the outer wall E. Similar guides P' are arranged transversely of the 90 guides P so that together these guides will hold the two walls accurately centered. Q is the outer imperforate wall of the burner 95 surrounding the foraminous tube E.

In operation, whenever the liquid fuel is 100 introduced into the base ring A through suitable valve-controlled connecting conduit, such as indicated at R, the liquid will be distributed around the ring and a portion will be absorbed by the wick L. To light the burner the inner wall B is lifted by means of the handle O and the burner K is also drawn upward to permit of lighting the wick. The wall D is then replaced, which will lower the lighter into the base ring and will initiate 105 the generation of the vapor. As soon as sufficient heat is imparted to the base ring to 110

vaporize the oil the flame of the lighter will be extinguished and the vapor will rise in the tube to burn with a blue flame therein and at the top thereof.

5 It will be noted that the downturned portion I of the cap G restricts the connection between the outer portion of the base ring and the portion thereof which is in alignment with the burner tube. This will permit the distribution of the vapor uniformly around the tube, having equal quantities in all portions thereof and thereby insuring a uniform flame.

What I claim as my invention is:

- 15 1. A vapor burner, comprising a base-ring having an upward foraminous extension, a detachable foraminous wall complementary to said upward extension, a coöperating foraminous wall rising from said base-ring to form an annular burner tube, and a lighter depending from said complementary foraminous wall, normally arranged in said base-ring and adapted to be lifted with the wall to which it is attached.
- 25 2. A vapor burner, comprising a base-ring having its inner wall extended upward and foraminous, a detachable foraminous wall complementary to said upward extension, an outer foraminous wall surrounding said inner wall and spaced therefrom, an annular lighter normally arranged in said base-ring, and hangers connecting said lighter to said complementary inner wall, for the purpose described.
- 35 3. A vapor burner, comprising a base-ring having its inner wall provided with a foraminous upward extension, a detachable foraminous wall forming a complementary portion of said inner wall, a coöperating outer foraminous wall of greater diameter extending upward from said base, a lifting handle at the upper end of said inner wall, and a lighter ring in said base-ring having hangers for connecting the same with the complementary portion of said inner wall, whereby in the lifting of said inner wall the lighter is also lifted.
- 45 4. In a vapor burner, the combination with a base ring and inner and outer fo-

raminous walls rising therefrom forming a 50 burner tube, one of said walls being upwardly detachable from the burner, of a lighter normally arranged in said ring, the detachable wall being connected to said lighter and forming a means for lifting the 55 same.

5. In a vapor burner, the combination with a base ring and inner and outer foraminous walls rising therefrom forming a 60 burner tube, one of said walls being upwardly detachable from the burner, of a lighter normally arranged in said ring, the removable wall being connected to said lighter and forming a means for lifting the 65 same, and a handle member secured to said detachable wall.

6. In a vapor burner, the combination with a base ring and inner and outer foraminous walls rising therefrom forming a 70 burner tube, one of said walls being upwardly detachable from the burner, of a lighter normally arranged in said ring, the removable wall being connected to said lighter and forming a means for lifting the 75 same, and means carried by one of said walls engageable with the other to guide the detachable member and center the same.

7. In a vapor burner, the combination with a base ring and inner and outer walls rising therefrom forming a burner tube, one 80 of said walls being upwardly detachable from the burner, the removable wall being connected to said lighter and forming a means for lifting the same, and a handle 85 for the detachable wall having portions engageable between the walls to relatively center said walls.

8. A vapor burner, comprising a base ring having an upward extension, a detachable foraminous wall complementary to said upward extension, a coöperating foraminous wall rising from said base ring to form an annular burner tube, and a lighter detachably connected to the complementary foraminous wall to be lifted therewith and 95 normally arranged in said base ring.

In testimony whereof I affix my signature.
EDWIN G. MUMMERY.
